CLAIM

The ornamental design for an electronic device, as shown and described.

DESCRIPTION

FIG. 1 is a front, top, right side axonometric view of an electronic device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a rear, bottom, left side axonometric view thereof. FIG. 9 is an enlarged view of portion 9, shown in FIG. 1; and,

FIG. 10 is a perspective view of the electronic device of FIG. 1, shown in a state of use with additional environmental subject matter.

The broken lines in FIG. 10 that show a keyboard dock depict portions of the electronic device that form no part of the claimed design. The broken lines seen defining enlarged portion 9 in FIG. 1 and surrounding enlarged view in FIG. 9 represent boundaries of the enlarged portions and form no part of the claimed design. All other broken lines seen in the drawings depict environmental subject matter.
